UNITED STATES PATENT OFFICE

2,500,529

TOOTHPICK DISPENSER

Walter G. Drugas, Huntington Park, Calif.

Application September 30, 1948, Serial No. 51,965

2 Claims. (Cl. 312—73)

1

This invention relates to new and useful improvements and structural refinements in dispensers for toothpicks, and the principal object of the invention is to facilitate individual dispensing of toothpicks in a manner which prevents a toothpick from being reinserted in the dispenser after it is withdrawn therefrom.

By virtue of this arrangement, the instant dispenser is of a highly sanitary nature, and another feature of the invention resides in its ability to releasably retain a toothpick in an outwardly projecting position after the dispenser has been inverted, so that the projecting toothpick may be conveniently grasped and withdrawn in readiness for use.

Some of the advantages of the invention reside in its simplicity of construction, convenience of operation, and in its adaptability to economical manufacture.

With the above more important objects and features in view, and such other objects and features as may become apparent as this specification proceeds, the invention consists essentially of the arrangement and construction of parts as illustrated in the accompanying drawings, in which:

Figure 1 is a perspective view of the invention, the same being shown in an inverted dispensing position;

Figure 2 is a cross-sectional view, taken substantially in the plane of lines 2—2 of Figure 1;

Figure 3 is a cross-sectional view, taken substantially in the plane of the line 3—3 in Figure 2; and

Figure 4 is a plan view of the dispensing cap used in the invention, the same being taken in the direction of the arrow 4 in Figure 2.

Like characters of reference are employed to designate like parts in the specification and throughout the several views.

Referring now to the accompanying drawings in detail, the invention consists of a toothpick dispenser designated generally by the reference character 10, the same embodying in its construction a suitable, preferably transparent, receptacle 12 provided with a screw-threaded mouth portion 14 to removably receive a dispensing cap designated generally by the reference character 16.

The essence of novelty of the invention resides in the structural arrangement of the cap 16, the same preferably assuming the form of a dome-shaped body formed at the center thereof with a toothpick outlet opening 18, the cap body 16 being suitably screw-threaded to facili-

2

tate removable mounting thereof on the screw-threaded mouth portion 14 of the receptacle 12, substantially as shown.

A pair of protuberances 20 are formed integrally at the diametrically opposite sides of the cap body 16, these protuberances being formed with what may be referred to as recesses or pockets 22, best shown in Figure 2, in which are securely anchored outwardly angulated end portions 24 of a pair of resilient check straps 26.

These straps extend radially with respect to the opening 18 in the cap 16 and have their inner end portions overlapped as indicated at 28 in Figures 1 and 2.

15 The overlapped inner end portions of the straps 26 are formed with substantially semi-circular notches which, by virtue of the overlapped relationship of these straps, coact together in defining what may be called an aperture 30 (see Figures 3 and 4).

16 The straps 26 normally rest upon the cap body 16, and it is to be noted that when the straps are so disposed, the opening 30 is substantially smaller in diameter than the opening 18, the purpose of which arrangement will be herein-25 after more fully described.

17 When the invention is placed in use, toothpicks, preferably those of a circular cross-sectional configuration, may be placed in the receptacle as indicated at 32 in Figures 1 and 2, this, of course, being effected by removing the cap 16 from the receptacle so that the toothpicks may be inserted in the latter.

Thereupon, the cap 16 is applied to the receptacle and when it is desired to dispense a toothpick, the entire device is inverted so that one of the toothpicks 32 (by virtue of the dome-shaped configuration of the cap 16) will fall into the opening 18 and will project outwardly from the dispenser through the aperture 30. It should be understood that the aperture 30 is normally smaller in diameter than the toothpick, so that the toothpick will be effectively retained by the straps 26 in a projecting position and in readiness for withdrawal and use, as indicated at 34 in Figure 1.

50 The projecting toothpick may be readily and conveniently withdrawn from the dispenser in the direction of the arrow 36 in Figure 1, during which action the straps 26, being in frictional engagement with the projecting toothpick, will be caused to yield outwardly as indicated at 38 in Figure 2, so that the aperture 30 will be substantially enlarged to facilitate outward passage of the toothpick therethrough. As will be clearly

apparent, the toothpicks are usually provided with tapered end portions, which feature renders them readily adaptable for use in association with the instant device.

Needless to say, while the straps 26 are sprung outwardly in order to facilitate passage of a toothpick through the aperture 30, the straps will become disengaged from the cap body 16 but, by virtue of their inherent resiliency, they will automatically return to their initial positions in contact with the cap body, as soon as the toothpick is withdrawn.

In any event, it is to be particularly noted that after a toothpick is withdrawn through the openings 18, 30, it cannot be reinserted in the receptacle 12, inasmuch as the straps 26 defining the opening 30 and engaging the cap 16 cannot be sprung inwardly, while outward springing thereof will not be encouraged by an attempt to reinsert the toothpicks, so that the relatively small aperture 30 will effectively prevent reinsertion of the toothpicks into the receptacle 12, as will be clearly apparent.

It is believed that the advantages and use of the invention will be clearly understood from the foregoing disclosure and accordingly, further description thereof at this point is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

1. In a toothpick dispenser, the combination of a receptacle, a cap positioned thereon and provided with a dispensing opening, and a pair of resilient straps having outer ends secured to said

cap and extending radially toward said opening, inner end portions of said straps being overlapped and formed with notches coacting to form an aperture in register with and of a smaller diameter than said opening and smaller than the thickness of the toothpick which is to be dispensed, said straps normally resting on said cap but being yieldable in response to outward pulling of a toothpick through said opening whereby the overlapped end portions thereof tend to separate and enlarge said aperture to facilitate outward passage of the toothpick therethrough.

2. A toothpick dispensing cap adapted to be mounted on a receptacle and comprising a dome-shaped shell provided at the center thereof with a dispensing opening, a pair of pockets provided exteriorly at diametrically opposite sides of said shell adjacent the marginal edge of the latter, and a pair of resilient straps disposed exteriorly of the shell and each having an angulated end portion secured in one of said pockets, free end portions of said straps being overlapped and provided in end edges thereof with coacting notches defining a toothpick receiving aperture in register with said opening, said aperture being smaller than the opening when at least one of the straps abuts the outer surface of the shell but being expandable by a movement of the straps away from said surface.
